(57) **CLAIM**

The ornamental design for a hair dryer, as shown and
described.

DESCRIPTION

FIG. 1 is a front perspective view of a hair dryer, showing
my new design;

FIG. 2 is a top plan view thereof;

FIG. 3 is a front elevational view thereof;

FIG. 4 is a rear elevational view thereof; and,

FIG. 5 is a side elevational view thereof, the opposite side
being a mirror image thereof.
